OVERSHOE

Emma J. Klinker, Los Angeles, Calif.

Application November 7, 1955, Serial No. 38,776

Term of patent 7 years

(Cl. D7—4)

Figure 1 is a view in perspective as viewed from the front and right side of an overshoе embodying my new design; and

I claim:

The ornamental design for an overshoе, substantially as shown.
